(57) **CLAIM**

The ornamental design of an output panel for a computer power supply, as shown and described.

DESCRIPTION

FIG. 1 is a perspective view of an output panel for a computer power supply, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines showing the remaining portions of a computer power supply in the Figs. is for illustrative purposes only and forms no part of the claimed design.
